E. Kupferle

UNITED STATES PATENT OFFICE.

EDWARD KUPFERLE, OF ST. LOUIS, MISSOURI.

MEASURING PUMP.

981,061.

Specification of Letters Patent Patented Jan. 17, 1911.

Application filed December 2, 1909. Serial No. 531,001.

To all whom it may concern:

Be it known that I, EDWARD KUPFERLE, a citizen of the United States of America, residing in the city of St. Louis and State of Missouri, have invented certain new and useful improvements in Measuring Pumps, of which the following is a full, clear, and exact description, reference being had to the accompanying drawings, forming part 10 of this specification.

My invention relates to a pump, and has for its object the production of a pump having means for accurately measuring and indicating the quantity of fluid displaced during each of its operations.

In the drawings: Figure I is a side elevation, partly in section. Fig. II is an enlarged side elevation, partly in section, of the upper portion of the pump. Fig. III 20 is a plan view. Fig. IV is a detail view illustrating means for locking the pump in the position shown in Fig. I. Fig. V is a section on the line V—V, Fig. II. Fig. VI is a section on line VI—VI, Fig. II. Fig. VII 25 is a perspective view of an adjustable stop member. Fig. VIII is a view similar to Fig. VII, of the stop member as seen from another position.

A indicates a well provided with an intake pipe 1, and having an outlet 2, a check valve 3 being arranged at said outlet. A pump cylinder 4 is mounted on the well A and connected thereto by rods 5 which pass through lugs on the well and on the cylinder head 6.

7 indicates a vertically movable piston provided with a check valve 8. The piston rod 9 is secured to a rack bar 10 which meshes with a pinion 11. A housing 12, in which the pinion 11 is located, is mounted on a post 13, the latter being secured to the cylinder head 6. The pinion 11 and handle 14 for operating it are secured to a shaft 15. It will now be understood that the handle 14 and pinion 11 may be operated to cause the rack bar, piston rod and piston to reciprocate vertically.

An indicator B, which may be provided with any suitable counting mechanism, is preferably secured to the housing 12. The vertically movable rack bar 10 has a projection 10^a located in alignment with the arm 16 which projects from the indicator B, (see Figs. I and III). When the handle is operated to cause the rack bar and piston to move to their extreme upper positions, the

projection 10^a elevates the indicator arm 16, and thereby actuates the indicator B. The function of this indicator is to register the number of full strokes made by the piston. 60

I will now describe the means for locking the mechanism in the position shown, means for unlocking said mechanism and allowing the piston to be moved a predetermined distance, and means for indicating 65 the quantity of fluid discharged from the pump cylinder during such operation of the piston.

18 indicates a tube having a threaded end 70 screwed into the cylinder head 6, its opposite end being fitted in the housing 12. C indicates a rotatable rod mounted in the tube 18, said rod having journals 19 and 20, respectively, (see Fig. II). The journal 19 is rotatably mounted in a bearing 21, screwed 75 into the housing 12; the journal 20 being stepped in the cylinder head 6. An adjustable sleeve 22 is screwed on the lower portion of the rod C and held in position by means of a set screw 23 (see Figs. II and 80 V). Recesses 22^a are formed in the periphery of the sleeve 22 for the reception of a suitable adjusting tool, a plurality of said recesses being aligned with the slot 18^a in the tube 18 (see Fig. V).

The lower portion of the rod C is provided with flat faces which terminate at shoulders P, Q, G' and G, respectively. These shoulders are located in different horizontal planes and different vertical planes, and it will be 85 seen that by revolving the rod C, any one of said shoulders can be located in alignment with the extension 10^a on the rack bar 10. The rack bar 10 is normally locked in lowered position by the shoulder 24 on the rod C which cooperates with the extension 10^a.

An indicator dial 25 is rigidly secured to the upper end of the rod C for the purpose of indicating the adjustment of said rod. When the parts occupy the adjusted position 100 shown, the word "Lock" appears opposite a stationary pointer 26 (see Fig. III), and lugs 27 on the under side of the dial 25 are aligned with the key lock 28 (see Fig. IV). For the purpose of illustrating the use of 105 this invention, I have shown the indicator dial 25 provided with characters indicating one pint, one quart, $\frac{1}{2}$ gallon, and one gallon, the character 1 Qt. being shown in dotted lines in Fig. III. When one of these characters appears opposite the pointer 26, it indicates that a certain shoulder on the rod C, 110

is located in alignment with, and adapted to constitute a stop for the rack bar extension 10. 1-Pt. indicates that the shoulder P is effective, and when the indicator occupies this position, the piston can be raised until the rack bar engages said shoulder, this movement of the piston causing one pint of fluid to be discharged through the discharge 29. When the character 1-Qt. appears at the pointer 26, the shoulder Q is aligned with the rack bar extension 10, and the pump is operable to discharge one quart. 3-Gal. indicates that the shoulder G' is aligned with the rack bar, and 1-Gal. indicates that the shoulder G is in said position.

The upper face of the housing 12 is preferably provided with recesses 30 adapted to receive a spring-pressed detent 31, the latter being mounted in the dial handle 32. 33 is 20 a collar on the detent 31 and against which the spring 34 presses. When the dial is in any adjusted position, the detent 31 is pressed into one of the recesses 30.

To procure accurate measurement, it is 25 essential that the rack bar extension 10 occupy a normal or starting position, a certain distance away from the stops on the rod C. Owing to the fact that friction at the lower end of the journal 20 and hammer blows 30 which occur when the extension 10 strikes the sleeve 22, cause these parts to wear, the device would become inaccurate if adjustable means were not provided for stopping the rack bar in its lowermost position. I, therefore, consider the adjustable sleeve, or stop member, 22 one of the important parts of this invention because it enables the measuring elements to be accurately adjusted to their proper position. The bearing 21 is 40 also brought into service as an adjusting device when the lower end of the journal 20 becomes worn. In this event, the upper end of the rod C would be spaced away from the bearing 21, and the rack bar could therefore 45 continue to move upwardly after it had engaged one of the stops on rod C. However, this excess movement can be prevented by screwing the bearing 21 downwardly into engagement with the rod C.

50 I claim:

1. A measuring pump, comprising a well, a pump cylinder having a discharge at its upper end and mounted on the well, a cylinder head, a piston provided with a check 55 valve and vertically movable in the pump cylinder, a piston rod, a rack bar having a lateral projection and a lateral extension

and surmounting and secured to the piston rod, a post and a tube mounted on the cylinder head, a housing mounted on the post 60 and the tube, an indicator having an arm engaged by the rack-bar-projection and mounted in the housing, a pinion for operation of the rack bar, and a rotatable rod having flat faces providing shoulders at different heights adapted to be engaged by the lateral extension and mounted in the pump head and housing.

2. A measuring pump comprising a well, a pump cylinder having a discharge at its 70 upper end and mounted on the well, a cylinder head, a piston provided with a check valve and vertically movable in the pump cylinder, a piston rod, a rack bar having a lateral projection and a lateral extension 75 and surmounting and secured to the piston rod, a post and a tube mounted on the cylinder head, a housing mounted on the post and the tube, an indicator having an arm engaged by the rack-bar-projection and mounted 80 in the housing, a pinion for operation of the rack bar, a rotatable rod having flat faces providing shoulders at different heights adapted to be engaged by the lateral extension and mounted in the pump head and housing, and an adjustable internally screw threaded sleeve working on and supporting the lower end of the rotatable rod.

3. A measuring pump comprising a well, a pump cylinder having a discharge at its 90 upper end and mounted on the well, a cylinder head, a piston provided with a check valve and vertically movable in the pump cylinder, a piston rod, a rack bar having a lateral projection and a lateral extension 95 and surmounting and secured to the piston rod, a post and a tube mounted on the cylinder head, a housing having recesses and mounted on the post and the tube, an indicator having an arm engaged by the rack-bar-projection and mounted in the housing, a pinion for operation of the rack bar, a rotatable rod having flat faces providing shoulders at different heights adapted to be engaged by the lateral extension and mounted 100 in the pump head and housing, an indicator dial having a handle and secured to the upper end of the rotatable rod, and a detent in the handle adapted to engage the recesses in the housing.

EDWARD KUPFERLE.
